UNITED STATES PATENT OFFICE.

CHARLES D. McDONALD, OF CHICAGO, ILLINOIS, ASSIGNOR, BY MESNE ASSIGNMENTS, TO AMERICAN CORK & SEAL COMPANY, OF PHILADELPHIA, PENNSYLVANIA, A CORPORATION OF MAINE.

MACHINE FOR FORMING SEALS IN METALLIC CAPS.

1,013,841.

Specification of Letters Patent.

Patented Jan. 2, 1912.

Application filed October 28, 1909. Serial No. 525,170.

To all whom it may concern:

Be it known that I, CHARLES D. McDONALD, a citizen of the United States, residing at Chicago, in the county of Cook and State 5 of Illinois, have invented certain new and useful Improvements in Machines for Forming Seals in Metallic Caps, of which the following is a specification.

The object of the present invention is to 10 produce a combination of mechanisms which will automatically form and position a seal in the interior of a metallic cap of the type ordinarily employed to form bottle closures; and the invention relates to mechanism for 15 forming and placing a sealing substance in proper position within said cap and to forming and securing within the cap a retaining member for the sealing substance; to means for automatically feeding a strip of 20 sealing substance into position to be cut into sections; to means for automatically performing the cutting operation; to means for automatically carrying the sections into 25 position to be placed into the cap; to means for automatically feeding the caps into position to receive the sections; to means for 30 automatically feeding a strip of metal; to means for automatically stamping out retaining members for the sealing substance 35 from said metal; to means for automatically positioning and securing said retaining members in place within the cap; to means for actuating the various mechanisms from a common drive shaft; and to means for 40 automatically adjusting the mechanism after each operation, so as to keep the various parts in proper relation with one another. And the invention further consists in the features of construction and combination of parts hereinafter described and claimed.

In the drawings, Figure 1 is a longitudinal section of the entire machine; Fig. 2 a top or plan view; Fig. 3 a section on line 3—3 of Fig. 1; Fig. 4 a section on line 4—4 45 of Fig. 1; Fig. 5 an enlarged sectional detail of the mechanism for cutting the sealing substance into sections; Fig. 6 a detail taken on line 6—6 of Fig. 1 of the mechanism for transmitting power to bring the sections 50 of sealing substance into position for insertion into the cap and for transmitting power to bring the cap into position to receive the sealing substance and the retaining members for the sealing substance; Fig. 7 a side view

of the parts shown in Fig. 6; Fig. 8 a section of the completed cap; Fig. 9 a perspective of the retaining member for the sealing substance; Fig. 10 a perspective of a section of sealing substance; Fig. 11 a detail showing the ratchets for operating the feed rolls 60 to bring the sealing substance into position to be cut into sections; and Fig. 12 a plan view of said ratchets, taken on line 12—12 of Fig. 4.

The mechanism is positioned upon a 65 frame work composed of a base 11, side walls 12, which have openings 13 formed therein, end walls 14 and 15, and a top wall or plate 16. Extending from the base 11 is an upright standard or support 17, in which one 70 end of a driving shaft 18 finds a bearing. Affixed to the driving shaft 18 and lying adjacent the support 17 is a main driving pulley 19, and affixed to the other end of the driving shaft is a driving gear wheel 20, 75 which meshes with a driven gear wheel 21, the driving gear wheel and the driven gear wheel being journaled in suitable sleeves extending out from the end wall 15 of the frame. Attached to the shaft carrying the 80 driven gear wheel 21 is a pulley 22, which drives a twisted belt 23, which extends over idlers 24 and around a rotatable head 25, carrying the mechanism for cutting the sealing substance into sections. The head 25 is 85 formed with a plurality of vertically extending openings 26, in which are positioned spring controlled swinging arms 27 pivotally mounted upon pins 28. Upon the lower 90 ends of the arms are rollers 29, which contact the sloping face of a ring 30. Affixed to the ring are rods 31, which extend up from a sliding bracket 32, actuated by a cam 33 fixedly secured to the driving shaft 18. Upon the upper surface of the head 95 25 are a plurality of cutting tools 34 carried by slidable arms 35 and adjustable in said arms. The head 25 is mounted upon a hollow sleeve 36 extending up from the top wall 16, and through an opening 37 in the sleeve 100 100 is fed a strip of sealing substance 38, of any known and suitable composition, which feeding is performed by companion feed rolls 39 mounted between ears depending from the top wall 16. To the rods carrying 105 the feed rolls are attached ratchets 40 and 40^a, operated by dogs 41 and 41^a, carried by an arm 42, actuated by a rod 43, to which motion

is imparted by means of a cam 44 attached to the main driving shaft 18. A double set of ratchets and dogs are necessary because of the fact that after a section has been cut 5 from the body of the sealing substance, the body portion must be retracted to allow the cut section to be carried into position for insertion in the cap, and to accomplish this a greater degree of movement must be imparted to the feed rolls when the substance 10 is fed into position to be cut, than when withdrawn from such position, the difference in movement being equal to the amount of material cut off. Therefore the ratchet 15 40^a which acts when the substance is withdrawn will have its teeth formed as shown in Figs. 11 and 12, which will produce a certain amount of lost motion in the action of the dog and rotate the rolls a lesser distance than they will be rotated by the ratchet 40.

Mounted in a sleeve 45 extending from the top wall 16 is a shaft 46, carrying a rotatable member composed of a plurality 25 of outwardly extending arms 47, in each of which is positioned a fixed hub 48, in which is mounted a slideable sleeve 49 held normally upward under spring tension. The sleeve 49 surrounds a pin 50, having an enlarged head 51, which, when brought into proper position, receives the end of the sealing substance as it is fed up, and in which is formed a groove 52, into which the edges of the cutting tools 34 enter after cutting 30 through the sealing substance, so that the cutting edges of the tools are not brought into contact with any metallic surface, thereby enabling the tools to be used for a long period of time without resharpening.

40 A slideable head 53 is positioned between upwardly extending guide plates 54 attached to a fixed table 55 formed with the frame work. The slideable head consists of an upper arm 56, in which is entered a pin 45 57, adapted, when the arm 47 carrying the sleeve 48 has been brought to proper position, to contact and move the sleeve, strip the sealing substance from the head 51, and deposit it within the cap. Attached to the 50 upper arm 56 and to a lower arm 58 of the slideable head are centering pins 59 and 59^a respectively, the pin 59 in the upper arm being adapted to enter a hole 59^b formed in a boss extending out from the arms 47. The 55 slideable head is further provided with a lug 60, to which is attached a rod 61 connected to a plate 62, carrying a roller which enters into the groove of a cam 63 attached to the main driving shaft 18.

60 Surrounding the fixed table 55 is a ring 64 formed in which are a plurality of recesses or pockets 65 adapted to be brought into register with the heads 51 carrying the sections of sealing substance, and into which 65 recesses or pockets metallic caps are en-

tered and into which recesses or pockets the caps are fed by any suitable or well known mechanism, and the caps lie within a countersunk portion of the recesses, which is best shown in Fig. 1. The ring 64 rests 70 upon and is attached to a ring 66, the rings 64 and 66 having holes 60^a formed therein, in which the pin 59^a on the lower arm 58 enters when the head 53 is lowered, the pins 59 and 59^a and the holes 59^b and 60^a providing means for bringing the arm 47 and ring 64 into proper position of adjustment after each movement. Attached to the ring 66 is a ring 67 provided around its outer edge with gear teeth 68, which mesh with the teeth of a pinion 69, carried by a stub shaft 70 mounted in a sleeve 71 depending from the top plate 16. Upon the lower end of the stub shaft is affixed a pinion 72, which meshes with a pinion 73 carried by the shaft 46, and below the pinion 72 is a miter gear 74 carried by the shaft 70, which meshes with a miter gear 75 carried by a shaft 76 journaled in sleeves 77 formed with the frame work.

90 Located upon the guide plates 54 and in the path of travel of the ring 64, is a receptacle 77^a for glue, or other adhesive substance, which has a valve located therein, actuated by an arm 77^b adapted to be contacted by a member 77^c located on the sliding head 53, which parts operate to place a drop of glue on the center of the interior of the caps as the caps are brought into position beneath the glue receptacle.

95 On the shaft 76 is a clutch 78, consisting of a member 79 fixed on the shaft and a member 80 loose on the shaft, and the loose member is provided with teeth 81 adapted to enter recesses 82 of the fixed member. The loose member is further provided with gear teeth 83 on its outer periphery, which mesh with the teeth of a rack 84 actuated by an eccentric 85 attached to the main driving shaft 18, the rack being held in engagement with the gear teeth by a bracket 86. With the upward movement of the rack 84, the loose member 80 will be rotated in a direction so that the teeth 81 will engage the recesses 82, move the fixed section 79, and rotate the shaft 76. When the rack moves downward, this will rotate the member 80 so as to withdraw the teeth 81 from engagement with the recesses 82 and impart no movement to the shaft.

100 110 115 120 125 130 Mounted between standards or uprights 87 extending from the table 55 is a reel 88, on which is wound a strip of aluminum, or other suitable metal, 89. The standards 87 also serve as guide plates for a slideable head 90, which carries a male forming die 91 and a male cutting die 92. Attached to the head 90 is a rod 93, which is attached to a plate 94, carrying a roller which travels in the groove of a cam 95 attached to the

main driving shaft 18. The strip of metal 89 passes under an idler 96 and travels across female dies 97 and 98, the former of which co-acts with the male die 91 to produce a depression 99 in the retaining member 100, and the latter of which co-acts with the male die member 92 to cut the retaining member out from the body portion of the strip of metal. The metal is fed forward 10 by feed rolls 101, actuated by a ratchet 102, rotated by a dog 103, carried by an arm 104, actuated by a rod 105, attached to an eccentric 106, and secured to the main driving shaft 18.

15 The operation is as follows: Power is applied to the driving pulley 19 to rotate the main driving shaft 18. This will rotate the gear wheel 21 and the pulley 22 and will transmit movement by the belt 23 to the head 26. The rotation of the shaft 18 will rotate the cam 33, causing the bracket 32 to move up and down, and its upward movement will cause the ring 30 to move upward, and the contact of the bevel face of the ring 28 with the rollers 29 will cause the top of the arm 27 to swing inwardly, carrying with it the cutting tool 34, and returning to normal position by spring pressure. The rotation of the shaft 18 will give movement to the cam 44, actuating the rod 43 and arm 42, causing one of the dogs 41 to engage in the teeth of one of the ratchets 40, actuating the feed rolls in proper direction to feed the strip of sealing substance upward until its 35 end has been positioned upon the head 51 on one of the pins 50 carried by one of the heads 48 in one of the arms 47. The movement of the mechanism is so timed that one of the heads 51 is always in position to receive the end of the sealing substance when it is fed upward. After the sealing substance has been fed onto the head 51, the cutting members are moved inwardly to engage the sealing substance, and the head and cutters revolved by the method previously described, to cut a layer off from the body portion of the sealing substance. After the cutting operation has been performed, the arms 47 are revolved in a step by step movement and the section of sealing substance upon the head 51 brought into position to register with the caps in the recesses 65, and when such position is reached, the head 53 will be drawn down, causing the pin 57 to 50 move the sleeve 49 down and strip the section of sealing substance off the head 51 and into position with the cap. After the sealing substance has been thus inserted, the ring 64 will be rotated step by step until the 55 cap is brought into position beneath the die 98, and while the cap is being brought to this position, a drop of glue, or other adhesive substance, is placed in the cap from the glue pot. When the cap reaches a position 60 below the die 98, the die 92 descends and

cuts the retaining member 100 out of the body portion of the strip of metal, and at the same operation places the retaining member into the body of the cap, where it is held by the adhesive substance.

70

I claim:

1. In a device of the class described, the combination of mechanism for feeding a strip of sealing substance into position to have a portion severed therefrom and for 75 retracting said substance after the severing operation, and means operatively connected to said feeding mechanism, whereby said substance is fed forward a greater distance than it is retracted, substantially as described.

2. In a device of the class described, the combination of a pair of oppositely disposed feed rolls co-operating to feed a strip of sealing substance into position to have a 85 portion severed therefrom and for retracting said substance after the severing operation, a pair of ratchets connected to one of said rolls, the teeth on one of the ratchets being spaced farther apart than the teeth 90 on the other, an arm positioned intermediate the ratchets, oppositely disposed pawls carried by said arm and engaging the ratchets, and mechanism operatively connected to the arm, for imparting a swinging movement thereto, substantially as described.

3. In a device of the class described, the combination of mechanism for feeding a strip of sealing substance into position to be 100 cut into sections, cutting tools for performing said cutting operation, a rotatable head, means for rotating said head, a pivotally mounted spring controlled arm carried by said head, mechanism operatively connected to said arm for imparting a swinging movement thereto, a slidably mounted horizontally extending cutter carried by said arm and held against swinging movement with said arm, and a connection between said arm and cutter, whereby the swinging movement of the arm will impart a rectilinear reciprocating movement to the cutter, substantially as described.

4. In a device of the class described, the combination of a rotatable member comprising a plurality of outwardly extending arms, a fixed pin carried by each of said arms, a head having a circumferential groove on each of said pins, onto which the sealing substance is fed prior to the cutting 115 operation and upon which the severed section is retained, means for moving the rotatable member in a step-by-step movement to bring the heads into position to receive the sealing substance and thence into position for placing the section of sealing substance into a metallic cap, and means for stripping the sealing substance off from said head and positioning it within a metallic cap, substantially as described.

5. In a device of the class described, the combination of a rotatable member comprising a plurality of outwardly extending arms, a fixed pin carried by each of said arms, a head of each of said pins adapted to retain a section of sealing substance, means for intermittently moving the rotatable member, a member surrounding said pin, and means operatively connected to said member for actuating it to strip the sealing substance off from said head and deposit it within a metallic cap, substantially as described.

6. In a device of the class described, the combination of a rotatable member comprising a plurality of outwardly extending arms, a fixed pin carried by each of said arms, a head having a circumferential groove on each of said pins onto which the sealing substance is fed prior to the cutting operation and upon which the severed section is retained, means for moving the rotatable member in a step by step movement to bring the heads into position to receive the sealing substance and thence into position for placing the section of sealing substance into a metallic cap, a slideable sleeve surrounding said pin, and means for actuating the slideable sleeve to strip the section of sealing substance off the head and position it within the metallic cap, substantially as described.

7. In a device of the class described, the combination of a rotatable member comprising a plurality of outwardly extending arms, a fixed pin carried by each of said arms, a head having a circumferential groove on each of said pins onto which the sealing substance is fed prior to the cutting operation and upon which the severed section is retained, means for moving the rotatable member in a step by step movement to bring the heads into position to receive the sealing substance and thence into position to place the section of sealing substance into a metallic cap, a slideable sleeve surrounding said pin, a slideable head actuated by means connected to the main driving shaft, and means attached to said slideable head for actuating the slideable sleeve to strip the section of sealing substance off the head and position it within the cap, substantially as described.

8. In a device of the class described, the combination of a rotatable member comprising a plurality of outwardly extending arms, a fixed pin carried by each of said arms, a head having a circumferential groove on each of said pins onto which the sealing substance is fed prior to the cutting operation and upon which the severed section is retained, a slideable sleeve surrounding said pin, means for actuating the slideable sleeve to strip the section of sealing substance off the head and position it within a metallic cap, and means connected to the main driv-

ing shaft for moving the rotatable member in a step by step movement to bring the head into position to receive the sealing substance and thence into position for placing the section of sealing substance into a metallic cap, substantially as described.

9. In a device of the class described, the combination of a rotatable member comprising a plurality of outwardly extending arms, a fixed pin carried by each of said arms, a head having a circumferential groove on each of said pins onto which the sealing substance is fed prior to the cutting operation and upon which the severed section is retained, a slideable sleeve surrounding said pin, means for actuating the slideable sleeve to strip the section of sealing substance off the head and position it within a metallic cap, means for moving the rotatable member in a step by step movement to bring the heads into position to receive the sealing substance and thence into position for placing the section of sealing substance into a metallic cap, and a member on the slideable head co-operating with a recess in the rotatable member to bring the rotatable member into proper position of adjustment after each movement, substantially as described.

10. In a device of the class described, the combination of mechanism for feeding a strip of sealing substance into position to be cut into sections, cutting tools for performing said cutting operation, means for advancing and withdrawing said cutting tools to and from operative position, means for rotating said cutting tools, a rotatable member comprising a plurality of outwardly extending arms, a fixed pin carried by each of said arms, a head on each of said pins onto which the sealing substance is fed prior to cutting and upon which the severed section is retained, a slideable member surrounding said pin, means for actuating the slideable member to strip the section of sealing substance off the head and position it within a metallic cap, and means for moving the rotatable member in a step by step movement to bring the heads on the pins into position to receive the sealing substance and thence into position for placing the section of sealing substance into the metallic cap, substantially as described.

11. In a device of the class described, the combination of mechanism for feeding a strip of sealing substance into position to be cut into sections, cutting tools for performing said cutting operation, means for advancing and withdrawing said cutting tools to and from operative position, means for rotating said cutting tools, a rotatable member comprising a plurality of outwardly extending arms, a fixed pin carried by each of said arms, a head on each of said pins onto which the sealing substance is fed prior to cutting and upon which the severed section

is retained, a slideable member surrounding said pin, a slideable head actuated by means connected to the main driving shaft, means attached to said slideable head for actuating 5 the slideable member to strip the section of sealing substance off the head and position it within a metallic cap, and means for moving the rotatable member in a step by step movement to bring the heads on the pins 10 into position to receive the sealing substance and thence into position to place the section of sealing substance into the metallic cap, substantially as described.

12. In a device of the class described, the 15 combination of mechanism for feeding a strip of sealing substance into position to be cut into sections, cutting tools for performing said cutting operation, means for advancing and withdrawing said cutting tools 20 to and from operative position, means for rotating said cutting tools, a rotatable member comprising a plurality of outwardly extending arms, a fixed pin carried by each of said arms, a head on each of said pins 25 onto which the sealing substance is fed prior to cutting and upon which the severed section is retained, a slideable member surrounding said pin, means for actuating the slideable member to strip the section of sealing 30 substance off the head and position it within a metallic cap, and means for moving the rotatable member in a step by step movement to bring the heads on the pins into position to receive the sealing substance and 35 thence into position for placing the section of sealing substance into the metallic cap, substantially as described.

13. In a device of the class described, the 40 combination of mechanism for feeding a strip of sealing substance into position to be cut into sections, means for automatically performing said cutting operation, a rotatable member, means connected to the main driving shaft for rotating said member in a 45 step by step movement, a plurality of fixed pins carried by said rotatable member, a head on each of said pins onto which the sealing substance is adapted to be fed prior to cutting and upon which the section severed from the body portion is retained, a 50 slideable sleeve surrounding said pin, means for actuating the slideable sleeve to strip the section of sealing substance off the head and position it within a metallic cap, means for 55 moving the rotatable member to bring the heads on the pins into position to receive the sealing substance and thence into position for placing the section of sealing substance into the metallic cap, and means for 60 automatically bringing the caps into position to receive the sealing substance, substantially as described.

14. In a device of the class described, the 65 combination of mechanism for feeding a strip of sealing substance into position to be

cut into sections, mechanism for automatically performing said cutting operation, a rotatable member, a plurality of fixed pins carried by said rotatable member, a head on each of said pins onto which the sealing 70 substance is fed prior to cutting and upon which the severed section is retained, a slideable sleeve surrounding said pin, means for actuating the slideable sleeve to strip the section of sealing substance off the head and 75 position it within a metallic cap, means for moving the rotatable member in a step by step movement to bring the heads on the pins into position to receive the sealing substance and thence into position for placing 80 the section of sealing substance into the metallic cap, and a rotatable ring having therein a plurality of recesses adapted to receive metallic caps, and means for rotating said ring in a step by step movement in unison 85 with the movement of the rotatable member, substantially as described.

15. In a device of the class described, the combination of mechanism for feeding a strip of sealing substance into position to be cut 90 into sections, means for automatically performing said cutting operation, a rotatable member, a plurality of fixed pins carried by said rotatable member, a head on each of said pins onto which the sealing substance is 95 fed prior to cutting and upon which the section severed from the body portion is retained, a slideable sleeve surrounding said pin, means for actuating the slideable sleeve to strip the section of sealing substance off the 100 head and position it within a metallic cap, means for moving the rotatable member in a step by step movement to bring the heads on the pins into position to receive the sealing substance and thence into position for placing the section of sealing substance into a metallic cap, a rotatable ring having therein a plurality of recesses adapted to receive metallic caps, a gear wheel attached to said ring, and means connected 105 to the main driving shaft to actuate said gear and rotate said ring in a step by step movement in unison with the movement of the rotatable member, substantially as described.

16. In a device of the class described, the combination of mechanism for feeding a strip of sealing substance into position to be cut into sections, means for automatically performing said cutting operation, a rotatable member, a plurality of fixed pins carried by the rotatable member, a head on each of said pins onto which the sealing substance is fed prior to cutting and upon which the section severed from the body portion is retained, a slideable sleeve surrounding said pin, means for actuating the slideable sleeve to strip the section of sealing substance off the head and position it within a metallic cap, means for moving the ro- 120 125 130

- tatable member in a step by step movement to bring the heads on the pins into position to receive the sealing substance and thence into position for placing the section of sealing substance into the metallic cap, a rotatable ring having therein a plurality of recesses adapted to receive metallic caps, a gear wheel attached to said ring, means connected to the main driving shaft to actuate said gear and rotate said ring in a step by step movement in unison with the movement of the rotatable ring, a receptacle for glue or other adhesive substance positioned in the line of travel of the metallic caps carried in the recesses in the rotatable ring, and means for permitting a drop of glue to be deposited in the metallic caps, substantially as described.
17. In a device of the class described, the combination of mechanism for feeding a strip of sealing substance into position to be cut into sections, means for automatically performing said cutting operation, a rotatable ring having a plurality of recesses therein adapted to carry metallic caps, means for automatically rotating said ring in a step by step movement, a rotatable member carrying the severed sections of sealing substance into position to be inserted within the cap, means for automatically performing said inserting operation, means for moving the rotatable member in a step by step movement in unison with the movement of the rotatable ring, a reel carrying a roll of sheet metal, means for feeding said sheet of metal forward in a step by step movement, a slideable head carrying a male forming die member and a male cutting die member for forming and cutting retaining members for the sealing substance out of the sheet of metal, means for actuating said slideable head, a female forming die member and a female cutting die member adapted to coöperate with the male forming and male cutting die members on the slideable head, the female cutting die member being located in the path of travel of the recesses in the revoluble ring, the same operation which cuts the retaining members from the sheet of metal positioning the members in proper position within the cap, and means for depositing a drop of adhesive substance into the cap prior to the positioning of the retaining members, substantially as described.
18. In a device of the class described, the combination of mechanism for feeding a strip of sealing substance into position to be cut into sections, means for automatically performing said cutting operation, a rotatable ring having a plurality of recesses therein adapted to carry metallic caps, means for automatically rotating said ring in a step by step movement, a rotatable member carrying the severed sections of sealing substance into position to be inserted within the cap, means for automatically performing said inserting operation, means for moving the rotatable member in a step by step movement in unison with the movement of the rotatable ring, a reel carrying a roll of sheet metal, means for feeding said sheet of metal forward in a step by step movement, a slideable head carrying a male forming die member and a male cutting die member for forming and cutting retaining members for the sealing substance out of the sheet of metal, means for actuating said slideable head, a female forming die member and a female cutting die member adapted to coöperate with the male forming and male cutting die members on the slideable head, the female cutting die member being located in the path of travel of the recesses in the revoluble ring, the same operation which cuts the retaining members from the sheet of metal positioning the members in proper position within the cap, and means for depositing a drop of adhesive substance into the cap prior to the positioning of the retaining members, substantially as described.
